2 Sheets-Sheet 2

UNITED STATES PATENT OFFICE.

ELMER F. PIDGEON, OF SPICELAND, INDIANA, ASSIGNOR OF ONE-HALF TO LUTHER O. DRAPER, OF SPICELAND, INDIANA.

COMBINED SHIELD AND BRACKET SUPPORT FOR DOUBLE SHADES.

Application filed March 10, 1927. Serial No. 174,275.

This invention relates to double window shades of that type wherein the rollers are supported in close proximity between the upper and lower ends of the window frame, and more particularly to the shields used in connection with shades of this type for the purpose of preventing light from passing through the gap or space between the rollers thereof.

10 The invention has for one of its objects to provide a light excluding shield of the character stated which shall be of such angular formation in cross section as to extend into the gap or space between the shade rollers in a manner to positively exclude the direct entrance of light between the shade rollers and also to greatly reduce the entrance of reflected light.

15 The invention has for a further object to provide a light excluding shield of the character stated wherein the cross sectional formation thereof shall be such as not to interfere with the free operation of the shades and such as to add such strength and rigidity thereto as to permit of its being made of comparatively light sheet metal and utilized as a base or support for the shade roller brackets.

20 The invention has for a further object to provide a light excluding shield of the character stated which may be secured flat against the inner faces of the window frame or to and between the jambs of the window frame.

25 The invention has for a still further object to provide a light excluding shield of the character stated which shall be adjustable as to length so as to permit of its ready application to window frames of different widths.

30 With the foregoing and other objects in view, the nature of which will become apparent as the description proceeds, the invention consists of the construction, combination and arrangement of parts hereinafter fully described and claimed, and illustrated in the accompanying drawings, wherein:

45 Figure 1 is an elevational view of a window construction equipped with a double shade embodying a combined light excluding shield and shade bracket support,

50 Figure 2 is a view in end elevation of the double shade and combined light excluding shield and shade bracket support,

55 Figure 3 is a sectional view taken on the horizontal plane indicated by the line 3-3 of Figure 1,

60 Figure 4 is a detail elevational view of the

combined light excluding shield and shade bracket support,

65 Figure 5 is an elevational view illustrating the application to a window construction of a slightly modified form of the combined light excluding shield and shade bracket support,

70 Figure 6 is a sectional view taken on the horizontal plane indicated by the line 6-6 of Figure 5, and

75 Figure 7 is a sectional view taken on the vertical plane indicated by the line 7-7 of Figure 5.

80 Referring to the drawings, by reference characters, 1 designates the frame of a window construction which is shown as equipped with a double shade and a combined light excluding shield and shade bracket support of which the latter is constructed in accordance with my invention. The lower shade 2 is mounted on a roller 3 and provided with a pull cord 4. The upper shade 5 is mounted on a roller 6 and provided with a pull cord 7 which passes about a combined pulley and cord catch secured to the top of the window frame 1. The roller 3 is supported by brackets 9 and the roller 6 by brackets 10, and said brackets are secured to the combined light excluding shield and support 11.

85 The shield and support 11 is made of sheet metal, and is of V-form in cross or vertical section. It is of greater length than the rollers 3 and 6, and is also of a length greater than the distance between the sides of the window frame 1. It is adapted to be secured flat against the inner faces of the window frame 1, and extends inwardly from the window frame and into the gap between the rollers 3 and 6. The lower and upper members 11^a and 11^b of the shield and support 11 are equal in width. An attaching flange 11^c extends downwardly from the lower edge of the member 11^a, and an attaching flange 11^d extends upwardly from the upper edge of the member 11^b. The attaching flanges 11^c and 11^d which extend throughout the entire length 90 of the shield and support 11, and which consist of two thicknesses of the metal from which the device is made, are arranged in a vertical plane, and are provided with openings for the reception of the screws 12. The brackets 9 are secured to the ends of the member 11^a by rivets 13, and the brackets 10 are secured to the ends of the member 11^b by rivets 14. The bases of the brackets 9 and 10

95 or attaching flanges 9^a and 10^a thereof, are 100 105 110

positioned in contact with the outer faces of the members 11^a and 11^b, and the rivets 13 and 14 engage said flanges and members.

As shown in Figures 5, 6 and 7, the shield and support, which is here designated 15, may be made adjustable as to length so as to adapt it for application to window frames of different widths. This form of the device comprises telescopically associated sections 15^a and 15^b, and may otherwise be constructed similar to the device shown in Figures 1-4. If desired this device may be provided at the ends thereof with attaching lugs or ears 16 to permit of its application to and between the jambs of the window frame 1. The ears or lugs 16 are arranged at right angles to and extend forwardly from the ends of the attaching flanges 15^c and 15^d of the device, and are provided with openings for the reception of fastening elements such as the screws 17. When this device is not provided with the ears or lugs 16, the attaching flanges 15^c and 15^d thereof are provided with openings for the reception of the fastening elements.

Due to its angular formation, the shield and support may be made of comparatively light metal and of sufficient rigidity and strength to prevent the bending or distortion thereof as the result of and during the adjustment of the shades. The attaching flanges of the device add strength and rigidity thereto, and permit it to be secured flat against the inner faces of a window frame. As the device is of angular or V-form in cross or vertical section, and as it extends inwardly from the window frame and into the space between the shade rollers, it will positively exclude the entrance of light between the shade rollers and reduce to the minimum the passage of reflected light between the shade rollers.

The device is simple, durable and efficient, it may be manufactured and sold at a comparatively low cost, and it may be painted or enameled in any desired color. The brackets which are arranged at right angles to planes of the angular related members of the shield, are of such length that when the shade rollers are mounted thereon said members will project into the space between the rollers, and the vertical flanges of the shield extend above the trunnion receiving openings of the brackets, whereby to effect the exclusion of the light as stated.

It should be understood that the drawings are merely illustrative and do not pretend to give exact proportions. Furthermore, the said drawings are illustrative of a preferred construction, it being my expectation that various changes and modifications may be made without departing from the spirit and scope of my invention.

What is claimed is:—

1. A combined shield and bracket support for double shades, comprising a light excluding shield of angular formation in vertical

section adapted to support double shade rollers thereon and having a vertical dimension greater than the corresponding dimension of the space between the rollers, and the shield being arranged at the outer sides of the rollers with its apex extending into the space between the rollers. 70

2. A combined shield and bracket support for double shades, comprising a light excluding shield of angular formation in vertical 75 section adapted to support double shade rollers thereon and having a vertical dimension greater than the corresponding dimension of the space between the rollers, the shield being arranged at the outer sides of the rollers with its apex extending into the space between the rollers, and brackets for the rollers and secured to the shield above and below the apex thereof. 80

3. A combined shield and bracket support for double shades, comprising a light excluding shield of angular formation in vertical section adapted to support double shade 85 rollers thereon and having a vertical dimension greater than the corresponding dimension of the space between the rollers, the shield being arranged at the outer sides of the rollers with its apex extending into the space between the rollers, flanges extending vertically from the upper and lower edges of the shield, and brackets for the rollers and secured to the shield between the apex thereof and the flanges. 90

4. A combined shield and bracket support for double shades, comprising a light excluding shield of angular formation in vertical section adapted to support double shade 95 rollers thereon and having a vertical dimension greater than the corresponding dimension of the space between the rollers, the shield being arranged at the outer sides of the rollers with its apex extending into the space between the rollers, and the shield presenting upper and lower members, and brackets for the rollers and secured to each of said members at right angles to the plane thereof. 100

5. A combined shield and bracket support for double shades, comprising a light excluding shield of angular formation in vertical section adapted to support double shade 115 rollers thereon and having a vertical dimension greater than the corresponding dimension of the space between the rollers, the shield being arranged at the outer sides of the rollers with its apex extending into the space between the rollers, and the shield consisting of telescopically associated parts, and attaching lugs carried by the outer ends of said parts. 120

6. A combined shield and bracket support 125 for double shades, comprising a light excluding shield adapted to support double shade rollers thereon and having a vertical dimension greater than the corresponding dimension of the space between the rollers, and the 130

shield being arranged at the outer sides of the rollers and having a portion of angular formation in vertical section extending into the space between the rollers.

- 5 7. A light excluding shield and bracket support for double shades, comprising a member V-shaped in cross section and forming a base for shade brackets secured on the sides of the member at each side of the angle
10 of the V-shape, said V-shape providing a rigid support for the shade brackets.

8. A light excluding shield and bracket

support for double shades, comprising a member formed of sheet metal and formed V-shaped in cross section, the flat sides of 15 said member providing supports for shade brackets secured perpendicularly thereto and providing means whereby the bases of said brackets are arranged in close proximity and the axes of shade rollers carried by the 20 brackets spaced remote from one another to accommodate shades of unusual length.

In testimony whereof I affix my signature.
ELMER F. PIDGEON.
